UNITED STATES PATENT OFFICE.

EARL F. HOUGH, OF OAKLAND, CALIFORNIA.

EGG-BEATER AND LIQUID-MIXER.

SPECIFICATION forming part of Letters Patent No. 325,840, dated September 8, 1885.

Application filed October 16, 1884. (No model.)

To all whom it may concern:

Be it known that I, EARL F. HOUGH, a citizen of the United States, residing at Oakland, in the county of Alameda and State of California, have invented a new and useful Egg-Beater and Liquor-Mixer, of which the following is a specification.

Referring to the accompanying drawings, forming a part of this specification, Figure 1 is a front elevation of my improved egg-beater and liquor-mixer. Fig. 2 is likewise a front elevation, partly in section.

Similar letters of reference are used to indicate like parts throughout the several figures.

The frame A consists of two strands of p'a'ed wire twisted so as to form a way for the operating-thimble B. The lower ends of these wires are arranged so as to form a basket or beaters, C, and the wires at this point are flattened so that the edges will cut into and divide up into small particles the contents of the vessel to be beaten. The beaters and their stem are composed of a single length of wire bent at the center of its length so as to form two loops which intersect each other at vertical right angles.

Immediately above the loop the two strands of wire are twisted together so as to form the spirally-grooved rod or stem, as shown, and which is traversed by the internally-spirally-grooved thimble B.

Near the base of the spiral stem I solder or otherwise securely fasten a collar, E, which limits the downward play or travel of the thimble B.

The upper end of the stem is surmounted by a hollow handle or cap, F, within which the stem revolves freely. The lower part of the bore of this cap is crossed by a diaphragm, 40 a, and one of the strands of the stem rests

against the under side thereof, while the other strand projects through the said diaphragm, and is furnished on its interior end with a small collar or lug, b, which prevents the withdrawal of the stem from the head, while 45 at the same time a free revolution is permitted.

Within the basket or beaters is placed the bowl of a spoon, D, which is soldered or otherwise securely fixed to the base of the 50 basket. By means of this spoon the contents of the tumbler or vessel are constantly thrown or drawn downward to the bottom of the vessel as the beaters are operated, and none of the contents is thrown out over the rim or 55 top of the vessel in which the mixing is performed. The spoon-bowl is made convex on one side and concave upon the other side, as shown.

Having thus described my invention, what I 60 claim, and desire to secure by Letters Patent, is—

In an egg-beater and liquor-mixer, the combination of the stem A and beaters C, formed of a single wire, said stem being composed of 65 two spirally-twisted strands, one of which is extended beyond the end of the other and provided at or near its end with a lug or collar, b, the internally-spirally-grooved thimble B, loosely mounted on said stem, and the hollow handle or cap F, having a perforated diaphragm or bearing, a, substantially as shown and described.

In testimony that I claim the foregoing I have hereunto set my hand and seal.

EARL F. HOUGH. [I. S.]

Witnesses:

C. W. M. SMITH,
WILMER BRADFORD.
